(57) **CLAIM**

The ornamental design for a bottle with ridged pattern as shown and described.

DESCRIPTION

FIG. 1 illustrates a perspective view of the bottle of the present invention.

FIG. 2 illustrates a front view of the bottle of the present invention.

FIG. 3 illustrates a side view of the right side of the bottle of the present invention.

FIG. 4 illustrates a rear view of the bottle of the present invention.

FIG. 5 illustrates a side view of the left side of the bottle of the present invention.

FIG. 6 illustrates a top view of the bottle of the present invention; and,

FIG. 7 illustrates a bottom view of the bottle of the present invention.

The claimed design is useful for containing substances, including liquid substances.

A characteristic feature of the design resides in the ridged pattern as illustrated in the drawing disclosure. The ridged pattern is three-dimensional, protruding from the surface of the bottle. The illustrated pattern includes a series of ridges spiraling downward from the top of the bottle. The ridges are formed by a series of indentations which are depressed into the surface of the bottle in regular increments to form an indentation at regular intervals. These indentations form the sides of each of the series of ridges, resulting in the protruding, ridged pattern. The three-dimensional nature of the ridged pattern is illustrated by the linear perspective of the drawings disclosure.

1 Claim, 7 Drawing Sheets
